CORE ORIENTING DEVICE

George F. Fermier, Houston, Tex., assignor to
 Reed Roller Bit Company, Houston, Tex., a corporation of Texas

Application January 8, 1940, Serial No. 312,820

3 Claims. (Cl. 255—1.4)

This invention relates to core marking devices to so mark the core that, when it has been extracted, it may be properly oriented for subterranean survey purposes.

In the conventional method of core drilling, the core is cut and extracted without means of complete orientation although sometimes an acid bottle or other means is used to determine the angle of drift. Accordingly, whereas the type and extent of the various strata can be determined by such a core, there is no way of ascertaining the angle of inclination of such strata. When the core shows the strata to be sloping, even if the drift of the well is known, it is impossible to know whether the slope of the strata is with or against the drift or transverse thereto. Therefore, in order to map the various strata, a great number of cores from different wells must be taken, and even then the configuration of the strata between wells must be estimated, with considerable percentage of error. I am aware that various core devices have been developed to increase the accuracy of data gathered therefrom but, as far as I am aware, no one has produced a means for orienting a core so that the exact slope of the strata can be obtained, similar to that embodied in my invention.

The primary object of my invention is to increase the accuracy of subterranean exploration by core drilling.

A further object is a positive means of orienting a core with respect to the ground from which it is taken.

Other objects and features may become evident from the following disclosure when taken in connection with the following drawing, in which:

Fig. 1 is a longitudinal cross-section of a core marking head embodying my invention;

Fig. 2 is a bottom plan view of the device shown in Fig. 1.

It is to be understood that the core marking device shown in the drawing will serve to mark the upper end of a core and for this purpose it will be mounted on some suitable means which will enable the operator to know or to determine the orientation of the marking device when it first contacts the core. Such means are well known. For the purpose of such mounting, I have shown the head as having a body 30 with a shank 31 having slots 32 therein to receive pins or bolts on the part on which the head is to be mounted. It will be understood, however, that the head 30 may be provided with any other desired means for mounting it.

In the embodiment shown in the drawing, the marking prongs 34 are held by means of bushings 47 threaded into the downwardly opening

holes 48. The prongs 34 consist of plunger like parts having marking points at their lower or protruding ends and piston-like parts formed on their upper ends. These piston-like parts serve to prevent the prongs from dropping out through the bushings 47 and serve as guides for the prongs within the holes 48. A common compartment or interconnecting passageway 49 serves to interconnect the holes 48, and the holes 48 and compartment or passageway 49 are filled with a resilient or fluent substance 50, such, for example, as soft rubber.

This provides resiliency for the prongs, and provides for each of them a yielding support so as to accommodate any unevenness in the surface contacted. Furthermore, if one prong is forced inwardly prior to any other, the compression of the body of material 50 will tend to simultaneously force outwardly the other prong or prongs.

By the means described above, I have produced a device which gives a positive means of orienting a core. I do not wish to be limited to the specific embodiment set out herein, but only by the scope of the appended claims.

I claim:

1. In a device of the class described, a casing, said casing having channels leading from the lower end thereof and communicating with a common channel within said casing, a prong in each of said channels movable vertically therein and fluent material filling all of said channels, whereby said prongs may adjust themselves to unevenness in the surface of the formation encountered.

2. In a device of the character described, a core marking head having a plurality of openings extending from its outer face toward its inner end interconnected inwardly of their outer ends, a pin for each of said openings, each pin having a part projecting from said head and a plunger-like part slidably carried in the corresponding opening in the head, and a substantially noncompressible fluent material substantially filling said openings and the connections therebetween inwardly from said pins, whereby when one of said pins is moved inwardly into its opening another of said pins will be moved outwardly.

3. In a device of the character described, a core marking head having a plurality of guideways therein, a marking pin slidably mounted in each of said guideways and having parts projecting from said head, and force transmitting means interconnecting said pins for causing outward movement of one of said pins upon inward movement of another thereof.

GEORGE F. FERMIER.
